UNITED STATES PATENT OFFICE.

THOMAS GRASON, OF MANCHESTER, ENGLAND.

IMPROVEMENT IN BOOTS AND SHOES.

Specification forming part of Letters Patent No. 14,146, dated September 6, 1864.

To all whom it may concern:

Be it known that I, THOMAS GRASON, of Manchester, in the county of Lancaster, in the Kingdom of Great Britain and Ireland, have invented certain Improvements in Boots, Shoes, and Other Coverings for the Feet; and I do hereby declare the following to be a full, clear, and exact description of the same, reference being had to the accompanying drawings, and to the letters of reference marked thereon.

My invention relates to the novel method of securing outer sole and heel pieces to the inner soles or upper-leather in boots, shoes, and other coverings for the feet, whereby such sole and heel pieces can be detached or removed, when required, and fresh ones attached at the pleasure of the wearer, *ad libitum*.

The improvement consists in the adaptation and use of **T** or **V** shaped dovetailed circular or other similar-formed ribs, elongated projections or runners, and corresponding grooves or channels, as a means of connection between the upper part and the sole and heel of the boot.

In order to enable others skilled in the art to make my invention, I will now proceed to describe the manner of carrying the same into effect.

On reference to the accompanying drawings, which form a part of this specification—Figure 1 represents the under side of a boot or shoe, having a dovetailed groove formed therein; and Fig. 2, is an inside view of the outward sole detached, having ribs or projections formed thereon corresponding to the grooves or channels in Fig. 1. Figs. 3 and 4 are respectively transverse sections of the upper and under soles when attached together, the upper plate in Fig. 3 having an open slot or groove and that in Fig. 4 having dovetailed grooves or slots formed in the solid metal. These grooves may either run transversely or longitudinally on the sole of the boot. Fig. 5 is a plan view of the heel, showing the circular **T** or dovetailed grooves, having a number of sliding pieces therein placed. Fig. 6 is a side section of such groove and a sliding piece with a “cricketer’s” spike thereto attached; Fig. 7, a section of the two plates, the bottom or sliding plate being provided with three descriptions of projections which may be worn in place of outer soles. Fig. 8 is a view of the

upper plate, to which the heel or sole is attached, supplied with a projecting bead or flange around its outer edge, for the purpose of shielding the sliding plate to which the heel or sole is attached, also giving the appearance of one plate. This arrangement may be reversed, if desirable—that is to say, forming the flange on the under or sliding plate. Fig. 9 is a side view of the heel, showing the method of fixing the bottom sole or heel by means of screws.

a a, Fig. 1, is the inner welt or sole, and *b* the outer sole. *c c* is the dovetail or other-shaped grooves into which are keyed the corresponding ribs or projections, *d*, for the purpose of locking such soles together. When the outer sole and heel have been firmly forced up into their right position, a spring-latch, *l*, or other convenient fastener, is caused to retain them in such position until removed, at the wearer's pleasure.

In Fig. 9, *f* is a metal plate secured in any convenient manner to the welt *a*. This metal plate *f* is the medium whereby the outer sole, *b*, is secured to the welt, such means of fixture being accomplished by the screws *g*.

In Figs. 5 and 6, *h* is the circular dovetailed groove, having sliding pieces *i* placed therein. These sliding pieces may be made to receive a screw, *k*, having a spike, square or any other convenient form of head, or may be made solid, of any material, and to project below the groove, as seen at *m*, or another modification of the same, as shown in Fig. 7, wherein screws are let through and countersunk into the under sliding plate. These screws may have any desired form of head screwed onto them, *a'*, *a''*, and *a'''* being three descriptions of such projections, which may be worn in place of outer soles.

Fig. 10 is another modification of my attachable and detachable heel. Fig. 11 is a back view, and Fig. 12 a side view of the same. In this modification I use a single plate only, fastened to the grooves, Figs. 13 and 14, recessed into the heel of the boot and secured thereto by means of screws. *n* represents a metal plate having two he grooves, *o*, upon its top surface, and countersunk holes for nails or screws to attach the leather to its bottom surface. This plate is prevented from sliding off either by a screw going through it into the leather, or it may be fastened by the plate

being turned upward at right angles at the front, having two or more screws securing it to the front of the heel.

The plates for the heels being made alike, they may be changed from right to left, or vice versa, whenever the outward or inward side of the heel is worn much lower than the opposite side thereof.

I wish it to be understood that this principle may be adopted without the use of metal plates, by having he and she grooves, slots, or runners made of the leather forming the sole or heel; but the utility of this method will bear no comparison to that of using the plates with the grooves, slots, or runners made of metal.

Having now described the nature of the said invention, together with the method of carrying the same into practical effect, I wish it to be distinctly understood that I do not

confine myself to the precise details, relative proportions, or dimensions hereinbefore described, as it will be readily seen that the same may be considerably varied without departing from the invention; but

What I claim as my invention, and desire to secure by Letters Patent, is—

Securing sole and heel pieces to the soles and upper-leather of boots and shoes and other coverings for the feet by the use of dovetailed or T-shaped projections and grooves, substantially as and for the purpose specified.

In testimony whereof I have signed my name to this specification in the presence of two subscribing witnesses.

THOMAS GRASON.
